SUB-CASING-HEAD TAKE-OFF FOR WELLS

William H. Brenot, Toledo, Ohio

Application September 3, 1940, Serial No. 355,191

2 Claims. (Cl. 103—179)

This invention relates to take-off device for pumping installations.

This invention has utility when incorporated as a take-off below the frost line from the casing of a water well with the pump head thereabove in normal position as to the casing.

Referring to the drawing:

Fig. 1 is a side elevation, with parts broken away, of a pumping head for a water well having adaptation showing the take-off herein for a pressure water discharge line from an intermediate chamber;

Fig. 2 is a section on the line II—II, Fig. 1, showing the take-off connection from this intermediate chamber;

Fig. 3 is a section on the line III—III, Fig. 2, showing the chamber which is effective for supplying the take-off; and

Fig. 4 is a section on the line IV—IV, Fig. 3, showing details of the partition-providing means and duct communications for this take-off chamber.

From ground line 1 there may be casing 2 extending into a water well. In this casing under the region of the rise of the water there is located water intake device 3 with pump 4 in tubing or pipe 5. This pipe 5 surrounds pump rod 6. For operating this pump 4 through this pump rod 6 there may be mounted at casing head 7 power jack device 8 operable by motor 9. This casing head 7 in normal practice would have outlet 10.

In many regions it may not be desirable to effect the liquid lift, say water, to the surface of the ground 1. In the climates where there is freezing or cold seasons it is important that in water wells there be no cut off of this water supply. Accordingly, importance arises to have the water take-off below the frost line. This is effected economically herein with the retention of the normal casing 2. It is only necessary to determine the drop distance which it is desired to have for the take-off, and with such determination, in lieu of continuous pump rod 6 from the pump 4 there may be portion 11 from the casing head 7 to have threaded terminus 12 to coupling 13. This coupling 13 is to threaded portion 14 (Fig. 4) of the pump rod 6 through collars 15 and gasket cups 16 located in tubing extension 17 having taper thread connection 18 from terminus 19 of pipe 20 having threaded connection 21 with collar 22. This collar 22 has additional internally threaded portion 23 into which the pipe 5 from the pump 4 may be threaded. There is thus provided a guide for the pump rod 6 in its ascent from the pump 4.

The collar 22 has, on the side away from the pump 4, a radially extending face 24 against which may be located compressible disk 25 of a substance to resist the character of liquid to be handled. In the instance such be a water well this may be of rubber. Opposing this flat face 24 on the opposite side of this self-sealing disk or packing 25 is collar 26 having convex face 27 which, as thrust against the compressible disk 25, has a tendency to cause such disk to expand in effecting more efficient packing against the inner side of the casing 2. Complementary to this flange-providing collar 26 and spaced therefrom by tube or cylindrical pipe section 28 is collar 29 also having convex face 30 against compressible disk 31 similar to the disk 25. On the side of this disk 30 away from the disk 25 is packing collar 32 having internally threaded portion 33 to provide mounting or carrying connection for the unit 15 herein from pipe 34 as having connection 35 with the casing head 7. In the set-up herein as locating the pair of expansible disks or packing 25, 31, in the position desired for locating chamber 36, access is had between the pipe 34 and about the 20 pump rod 11 with a wrench or tool to engage notches 37 in nut 38 having coaction with cylindrical portion of the thread portion 39 on the pipe 20. This means there is positive thrusting of the collar 32 toward the collar 22 effecting expansive action in compressing the disks 25, 31, into self-sealing partitions in the casing 2 for isolating the chamber 36.

Having effected the self-sealing for this unit as to the chamber 36 at the desired spacing below the frost line 40, there may be just necessary slight excavation effected from the surface 1 along a side of the casing 2, and at such point tap 41 effected through the casing 2 into the chamber 36. Additionally, tap 42 (Fig. 1) is 35 into the casing above the packing disk 31 and tap 43 below the packing disk 25. Into these two 40 taps 42, 43, may be thrust duct 44 which serves as an effective bypass, whereby from tap 45 (Fig. 3) in the pipe 34 any water seepage past the cups 45 46 may spill from chamber 46 in the pipe 34 to chamber 47 in the casing 2 above the chamber 36 and from thence drain by the duct 44 to chamber 48 below the partition 25. This is also effective brake for suction or vacuum disturbance 50 in any operation of the pump 4.

In the functioning of the pump head 8 in operating the pump rod, the lift of the liquid as water through the pipe 5 passes through the collar 22 into the pipe section 20. It may not ascend past the collars 15 and cups 16 at the

threaded portion 14 of the pump rod 6. From this pipe 20 there is a lateral opening or port 49 that this liquid or water may spill into chamber 50 about this pipe 20 and from thence through port 51 in the spacer pipe section 28 into chamber 36. From there it may discharge through the tap 41. This tap 41 (Fig. 2) is effectively sealed, say by gasket 52 held by yoke 53, with U-bolt 54 about the casing 2. This U-bolt 54 is anchored with the yoke 53 by nuts 55. One of the legs of this U-bolt 54 may carry washer 56 having hook terminus 57 as a clamp for engaging the duct 44 and holding such in locking position with the casing 2. This yoke 53 has internally-tapped portion 58, from which extends take-off pipe 59. The excavation for effecting this connection may now be filled with soil and thus not only anchor the duct 54 but be a protection against frost. This line 59 may go to the dwelling, stable, pressure supply elevated tank, or to oppose an air pressure in giving a pressure service system.

In accordance with the invention herein, a pump installation as having the casing may have in such casing away from such head a location of a take-off chamber with a take-off pipe therefrom. This take-off chamber 36 as having its partitions 25, 31, is thus one of direct communication to the take-off pipe 59 in the ascent of water from the submerged pump 4, with such take-off for water down in the casing 2 below the frost line. For any attention to the parts herein, it is only necessary to remove the casing head 1, then through the pipe 34 operate the wrench to cooperate with the notches 37 to back off the nut 38 as to the cylindrical threads 39. There is thus a release of the clamping action which tends to expand the partitions 25, 31, and the unit may be brought to the surface for attention to the unit or attention to the pump 4, as the occasion may require.

In some instances there may be omissions of the ducts or bypass 44 to communicate between the opposite sides of the unit, that is, for communication between remote sides of the partitions. In such instances, when there is other occasion for air supply into the chamber 48, such air may be entrained in the pumping system in such a way that in the hydropneumatic set-up it may be a supply of air sufficient for maintenance of the pressure.

In other instances wherein there is desirability for establishing the unit as such, in lieu of the bypass 44 exterior of the casing 2, duct 60 registers in small openings through the collar 32, compressible member 31, collar 29, with its intermediate yieldable loop portion 61, thence on through collar 26, disk packing 25, and through the collar 22. The compressing action causes the disk 25, 31, to operate as an effective seal in holding this duct 60 with the collars and this provides the bypass between the chamber 47 and the

chamber 48 and clear of the intermediate chamber 36.

What is claimed and it is desired to secure by Letters Patent is:

1. A casing provided with a conductor for liquid, a unit insertable in the casing to a station intermediate the length of the casing, said unit including a plurality of spaced partitions, a laterally ported pipe section, a pair of collars spaced by the pipe section and providing seats for a pair of said partitions, an additional pipe through the spacer pipe section, a third collar having threaded engagement with the additional pipe and thereby opposing the lower partition on the side away from the collar against the lower side of the pipe section, a fourth collar loose on the additional pipe above the upper partition, and a nut having threaded engagement with the additional pipe and seating against the fourth collar, said nut as there rotatable being effective through the pipe simultaneously to clamp a pair of the partitions with the seat-providing collars against the ported pipe section for such spaced pair of the partitions to cooperate with the casing to form a chamber in the casing, there being port-providing means through the casing from said chamber, a pump, and a riser pipe in the casing to the unit, said pipe having communication with the pump for liquid delivery through the additional pipe into the chamber for effecting delivery of liquid from the casing by way of the chamber and port means.

2. A casing provided with a conductor for liquid, a unit insertable in the casing to a station intermediate the length of the casing, said unit including a plurality of spaced partitions, a laterally ported pipe section, a pair of collars spaced by the pipe section and providing seats for a pair of said partitions, an additional pipe through the spacer pipe section, a third collar having threaded engagement with the additional pipe and thereby opposing the lower partition on the side away from the collar against the lower side of the pipe section, a fourth collar loose on the additional pipe above the upper partition, and a nut having threaded engagement with the additional pipe and seating against the fourth collar, said nut as there rotatable being effective through the pipe simultaneously to clamp a pair of the partitions with the seat-providing collars against the ported pipe section for such spaced pair of the partitions to cooperate with the casing to form a chamber in the casing, there being port-providing means through the casing from said chamber, a pump, a riser pipe in the casing to the unit, and a pump rod through the additional pipe and riser for liquid delivery through the additional pipe and ported pipe section into the chamber for liquid discharge from the chamber by way of the port means through the casing.
